(57) **CLAIM**

The ornamental design for a bucket work machine for a loader, as shown and described.

DESCRIPTION

FIG. 1 is a front view of a bucket work machine for a loader showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view thereof;

FIG. 9 is an enlarged front view of a portion thereof;

FIG. 10 is an enlarged front perspective view of a portion thereof;

FIG. 11 is an enlarged rear perspective view of a portion thereof;

FIG. 12 is an enlarged cross-sectional view of a portion thereof taken along lines 12-12 shown in FIG. 9;

FIG. 13 is a reference perspective view of a link member thereof;

FIG. 14 is an enlarged front perspective view of a portion thereof including a grayish portion;

FIG. 15 is an enlarged rear perspective view of a portion thereof including a grayish portion;

FIG. 16 is a partially vertically cutaway referential view of a crosswise intermediate portion of the front view thereof; and, FIG. 17 is a reference perspective view thereof showing a condition in use.

The broken line showings of FIGS. 1-17 are environmental only and not part of the claimed design.

The dashed-dotted line showings of FIGS. 1, 2, 7-11, 14 and 15 illustrate boundaries between the claimed design and environmental features and form no part of the claimed design.

FIG. 14 and FIG. 15 each include a grayish portion, the grayish portion is a portion for which partial design protection is sought.
